UNITED STATES PATENT OFFICE.

CHARLES A. OLSON, OF GENEVA, ILLINOIS, ASSIGNOR, BY MESNE ASSIGNMENTS, TO
GENEVA HEATER COMPANY, OF GENEVA, ILLINOIS, A CORPORATION OF ILLINOIS.

WATER HEATER.

Application filed November 16, 1918, Serial No. 262,894. Renewed July 8, 1922. Serial No. 573,632.

To all whom it may concern:

Be it known that I, CHARLES A. OLSON, a citizen of the United States, residing at Geneva, in the county of Kane and State of Illinois, have invented certain new and useful Improvements in Water Heaters, of which the following is a full, clear, and exact specification, taken in conjunction with the accompanying drawings, forming a part thereof.

My invention relates to improvements in the construction and arrangement of the water heating burner and the heating coil spirally arranged about it, and has reference more particularly to the provision of an elliptical or flattened form of coil whose plane of elongation is in substantial parallelism with the wall of the burner, the latter provided with gas jet outlets spirally arranged with reference to the flattened heating surface of the coils. The primary objects of the invention is to provide a coil having a minimum fluid space and constructed to present a maximum amount of heating surface to the jets, and in a predetermined zone of maximum temperature; and a coil wherein the velocity of the fluid passing therethrough is greatly increased thereby, rendering the heater practically instantaneous in character and preventing the deposit in the coil of scale or sediment which ordinarily finds lodgment in the ordinary coils of circular cross-section.

My invention, therefore, has for its aim generally to improve and simplify the construction and increase the efficiency and utility of such apparatus; and further contemplates certain novel details of construction, combination and arrangement of the parts of the improved apparatus, whereby certain advantages are attained, as will be more fully described hereinafter, and pointed out in the claims.

These, together with such other objects and advantages as are incident to my invention, I attain by means of a construction illustrated in preferred form in the accompanying drawings, wherein—

Figure 1 is a vertical sectional view of an apparatus embodying my invention;

Figure 2 is a similar view of a modification thereof;

Figure 3 represents a top plan view of the modification illustrated in Figure 2;

Figure 4 is an enlarged view illustrating

in detail the preferred relation of the elongated coil with reference to the jet; and

Figures 5 and 6 are enlarged views suggesting modified forms of the coil as are considered within the scope of the invention.

Referring to the drawings, a suitable casing for the heater is denoted at 7, and within this casing is centrally mounted a burner 8 which is provided with a gas intake 9 positioned over and in alignment with the customary mixer 10. This mixer is connected to a source of gas supply. Spirally surrounding the upper wall of the burner, and spaced a predetermined distance away from it, is a coil 11, elliptical in cross-section, whose inlet end 11^a is connected with a source of water supply, the outlet 11' leading to the customary water distributing outlets.

The burner 8 has its upper wall 13 apertured to provide the flame jets or outlets 12 which are arranged spirally to correspond with the spiral contour of the coil, so that the flame will impinge upon the flattened inner or heating surface 14 of the coil, the plane of elongation of which being at right-angles to the axes of the jets. The coil is desirably positioned so that the heating surface 14, as a matter of predetermined distance and uniform location from the outlets 12, has its central portion arranged in what would normally be the apices of the combustion zones of the series of flame jets. As so located, however, in each case the apex, as such, disappears and the zone of maximum temperature spreads out about and along the coil for some distance, as indicated somewhat in Figure 4 of the drawings. This improvement makes for extremely high efficiency, and one important factor in this respect resides in so arranging the jets as to follow the contour of the coil in the manner set forth. Furthermore, the superimposed overhanging relation of the flattened coil is such that each jet outlet is protected by the section of coil echeloned above it from water or other condensation which might drip from the casing top into the outlet and tend to clog it. This will readily be seen from an inspection of Figures 1 and 2.

The elongated or flattened coil in addition to presenting an ideal surface for the impinging flame, provides a narrow or thinned fluid channel 15 through which a ribbon-like stream of water may flow while in contact with the heating surface. In other

105 110

words, the arrangement provides for the contact of a minimum quantity of fluid against a maximum amount of heating surface which is itself placed in a zone of maximum temperature. Furthermore, the velocity of flow is so materially quickened that the amount of heat transmitted through the heating surface is increased, and to a degree where deposit of scale or sediment in the coil is prevented.

10. What I claim is:

1. In a water heater, the combination with a water pipe having a flat surface, of a burner arranged to direct a flame against said surface at right angles thereto, said burner and pipe being so spaced from each other as to cause the hottest gases of said flame to radiate in all directions from the center of the flame and in contact with said flat surface which extends in all directions from the point of impingement of the flame thereon.

2. In a water heater, the combination with a water pipe having a flat surface, of a burner arranged to direct a flame against said surface substantially at the center thereof and at right angles thereto, said burner and pipe being so spaced from each other as to cause the hottest gases of said flame to radiate in all directions from the center of the flame and in contact with said flat surface.

3. In a water heater, the combination with a water pipe having a flat surface, of a burner arranged to direct a flame against said surface at right angles thereto, said flat surface extending in all directions from the point of flame impingement thereon, said

burner and pipe being so spaced from each other as to cause the hottest gases of said flame to radiate in all directions from the center of the flame and in contact with said flat surface, said burner being of such flame producing capacity and said pipe being so proportioned to the volume of flame produced that said hottest gases lap both edges of said pipe in addition to said flat surface.

4. In a water heater, the combination with a coil of flattened water pipe, of a series of burners for heating the same, each of said burners being arranged to direct a flame at right angles to and on substantially the medial line of one of the flattened surfaces of said pipe, said burners being each so spaced from the pipe as to cause the hottest gases of the flame produced to radiate in all directions from the center of the flame and in contact with said flat surface of the pipe.

5. In a water heater, the combination with a coil of flattened water pipe, of a series of burners for heating the same, each of said burners being arranged to direct a flame at right angles to and on substantially the medial line of one of the flattened surfaces of said pipe, said burners being each so spaced from the pipe as to cause the hottest gases of the flame produced to radiate in all directions from the center of the flame and in contact with said flat surface of the pipe, the volume of flame produced by each of said burners being so related to the size of the said pipe that said hottest gases also lap both edges of said pipe contiguous to said flat surface.

CHARLES A. OLSON.
